[57] CLAIM

The ornamental design for an electrostatic discharge device for use with an electrical wall switch, as shown and described.

DESCRIPTION

FIG. 1 is a perspective view of an electrostatic discharge device for use with an electrical wall switch; FIG. 2 is a first side elevation view of the electrostatic discharge device for use with an electrical wall switch shown in FIG. 1;

FIG. 3 is a second side elevation view of the electrostatic discharge device for use with an electrical wall switch shown in FIG. 1, taken at a right angle to said first side elevation view;

FIG. 4 is a top plan view of the electrostatic discharge device for use with an electrical wall switch shown in FIG. 1;

FIG. 5 is a third side elevation view of the electrostatic discharge device for use with an electrical wall switch shown in FIG. 1, showing the side opposite to that shown in FIG. 3;

FIG. 6 is a fourth side elevation view of the electrostatic discharge device for use with an electrical wall switch shown in FIG. 1, showing the side opposite to that shown in FIG. 2; and,

FIG. 7 is a bottom plan view of the electrostatic discharge device for use with an electrical wall switch shown in FIG. 1.
